UNITED STATES PATENT OFFICE.

MARTIN NESTER, OF DETROIT, MICHIGAN.

DUMPING BODY.

Application filed June 13, 1921. Serial No. 477,806.

To all whom it may concern:

Be it known that I, MARTIN NESTER, a resident of Detroit, in the county of Wayne and State of Michigan, a citizen of the 5 United States, have invented certain new and useful Improvements in Dumping Bodies, of which the following is a specification.

My invention relates to improvements in 10 dumping bodies and refers particularly to a dumping body capable of connection with a frame or support and automatic to a degree in its operation of dumping and return to normal position.

15 The main object of my invention is the provision of a structure which may be supported upon suitable traction means to be transported to the desired place of use and which will operate with ease and facility 20 and automatically.

Another object of my invention is the provision of a dumping body construction which can be easily transported and which will be 25 of simple, durable and inexpensive construction and thoroughly efficient and reliable in operation, to produce a practical and useful mechanism of this character.

To attain the desired objects and such others as inhere to an invention of this 30 character my invention consists of a dumping apparatus embodying novel features of construction and combination of parts substantially as shown, described and particularly defined by the claim.

35 In order that the construction in detail and the operation of my invention may be more clearly understood and its many advantages be fully appreciated I have shown in the accompanying drawings a dumping 40 apparatus constructed according to my invention and in said drawings;

Fig. 1 represents a perspective view of the body or scoop and a portion of the frame upon which it is mounted the body being in 45 normal-position.

Fig. 2 represents a side elevation with the parts in a position they occupy when the body assumes dumping position.

Fig. 3 represents a side elevation with the 50 parts in normal or undumped attitude, and

Fig. 4 represents a top plan view of the supporting frame, guide racks and the mechanism for retaining and releasing the scoop or body.

Fig. 5 represents a view of the inner wall 55 or end of the bucket or body.

Referring by numeral to the drawings in which the same numbers are employed to denote the same parts in all the views:

The numeral 1 designates the rectangular 60 elongated supporting frame which may be mounted upon a suitable traction means or truck for transporting the apparatus to the desired place, the frame at one end being provided with depending hooks forming 65 stops or abutments 2, while strips 3 are secured to the frame by fastenings 4, to space said strips from the frame to receive the pins or studs 5, which provides a pair of racks, the purpose of which will presently 70 appear.

Also mounted in the frame at a suitable point thereon are the cross pieces 6, to which is secured the pair of ears 7, provided with slots 8, in which moves the pin or keeper 9, 75 which is connected to the spring actuated arm or rod 10, guided in the frame and operated through the medium of the lever 11 and lever connections 12, to withdraw said keeper 9, the keeper being normally forced 80 into locked position by the spring 13, and being moved from locked position by the action of the hand lever 11 and connection 12, as will be readily understood.

The body or scoop 14 is mounted upon the 85 frame adjacent the pair of racks and is provided with a rear vertical wall 15 and a front inclined dumping portion or wall 16 and upon the inclined wall is secured the pair of curved strips or blocks 17, which 90 are made preferably of wood or suitable cushioning material and to said blocks are secured the curved geared or toothed plates 18, which are adapted to engage or ride upon the pair of racks of the frame, said 95 toothed plates being formed at one end with heads 19, adapted as seen in Fig. 2 to engage the stop of the frame to limit the movement of the scoop in its dumped position, a spring and chain connection 20, being provided between the toothed plates and frame, while the vertical wall of the scoop carries stops 21, which are adapted to engage the frame, said vertical wall also carrying the inclined arm 22, formed with a 100 hook 23 to be engaged by the keeper 9 for sustaining the parts in the position shown in Fig. 3, the bucket being limited in its

105

movement and returned to normal position by the chain 24, and intermediate spring 25, which in connection with the spring and chain connection 20, 20', provides an automatic action for said scoop or body.

The operation of my automatic dumping body will be readily understood from the description when taken in connection with the drawings and attention is called to Fig. 10 3 which shows the parts in normal position with the scoop ready to be filled and when the scoop has been filled it is simply necessary to move the spring actuated latch which releases the hook 23 and permits the scoop 15 to assume the dumping position shown in Fig. 2, the connections between the scoop and frame causing the body or scoop to automatically return to normal position after the operation of dumping.

20 It will thus be seen that I provide a dumping apparatus which is automatic in its action, or returns to normal position as soon as the dumping has been effected, also that the structure as a whole is simple, compact 25 and durable, and capable of production at a comparatively low price; also that the apparatus may be readily carried upon a truck and that, generally, the construction will provide an efficient, desirable and practical dumping apparatus.

30 It will be noted that the bucket or body 14, is provided with the buffer or stop 21, which consists of two vertical parallel mem-

bers, as shown in Figure 5, which form counter balance weights, and also that the 35 racks 18, are provided each with a lug 27, which forms a keeper for the rods 26, which are guided in the ears 26', and are connected for operation at 28, to the levers 11, which features are of paramount importance and 40 greatly enhance the efficiency and usefulness of my invention.

I claim:

A device of the character described comprising a track, a pair of racks secured to 45 said track, a one-way dumping hopper having racks meshing with the racks of the track and along which the said hopper is adapted to roll, said hopper having a short vertical and long inclined end wall, an arm 50 extending downward from said vertical wall and formed with a hook, a sliding catch engaging said hook, a slotted guide for said catch and secured to the track, a spring for holding the catch in locked position and for 55 returning it to normal position, a hand lever fulcrumed to the track and connected to the latch for releasing said latch, and a sliding rod mounted under the track connected with the lever and normally engaging the hopper, 60 said rod being moved by the lever to release it from the hopper to permit tilting of said hopper.

In testimony whereof I hereunto affix my signature.

MARTIN NESTER.
